UNITED STATES PATENT OFFICE.

MORRIS U. BERNHEIM, OF CINCINNATI, OHIO, ASSIGNOR TO THE ALVEY-FERGUSON COMPANY, OF CINCINNATI, OHIO, A CORPORATION OF OHIO.

INDICATING MECHANISM.

1,238,059.

Specification of Letters Patent. Patented Aug. 21, 1917.

Original application filed June 1, 1909, Serial No. 499,837. Divided and this application filed January 4, 1912. Serial No. 669,466.

To all whom it may concern:

Be it known that I, MORRIS U. BERNHEIM, a citizen of the United States, residing at Cincinnati, in the county of Hamilton and State of Ohio, have invented new and useful Improvements in Indicating Mechanisms, of which the following is a specification.

This invention relates to indicating mechanism for the trucks of freight or baggage transferring systems of the style, for example, shown in my application which since the filing of the present application has become Letters Patent of the United States dated January 12, 1915, Number 1,124,271, of which the present application is a division.

Reference may be had to the aforesaid patent for a full understanding with reference to a system of transferring freight, baggage and the like of which the present invention may be regarded as an element, being more especially but not exclusively intended for use upon a truck which may usefully be employed in such a system. The truck which I have herein illustrated is shown, described and claimed in an application filed by me of even date herewith and which has become Letters Patent No. 1,124,267, dated January 12, 1915, to which patent reference may be had for a full understanding of the structure of one form of truck to which the present invention may desirably be applied. This particular construction of truck, however, is not essential to the present invention.

For the foregoing reasons, I shall not herein attempt to describe in detail either the system in its entirety or the particular construction of truck which I have illustrated as an example of one upon which the indicating means of the present invention may be employed; but I wish to call attention to the fact, as exemplifying an important purpose and utility of the indicating means herein set forth and claimed, that in my aforesaid Patent No. 1,124,271 there is disclosed a platform which is shown as extending around a freight shed and is provided with what is arbitrarily termed a main line, said main line being tapped at intervals by lateral switches, the spaces between the switches preferably corresponding to the distances between the doors of

cars which are being loaded or unloaded beside the platform. In the use of these systems, it is desirable to arrange a series of trains side by side and frequently on each side of a platform. Each of these trains has a particular designation and each car also has a particular designation. Thus, in a system of four tracks on each side of the platform, each track may be arbitrarily given a particular number, or other suitable designation, and the train thereon may take its designation therefrom: thus, train No. 1, train No. 2 and so on. The cars of each train further are given particular designations, as car No. 1, car No. 2 and so on. When more than one train are side by side, cars bearing corresponding numbers are side by side.

The present invention is more particularly adapted for use as an element of a system such as has been hereinbefore referred to, but it is not intended to restrict its application to the particular system set forth, as it is intended to employ it in any system of transferring freight, baggage or the like wherein a truck or carrier of the present character may be usefully employed.

In the drawings, wherein like characters of reference designate corresponding parts:

Figure 1 is a plan view of a truck embodying the present improvements, showing also a part of the platform.

Fig. 2 is a longitudinal section of the truck and a side view of a portion of its propelling chain.

Fig. 3 is a front view of the truck: and

Fig. 4 is a transverse section on the line 4-4 of Fig. 1.

Referring now particularly to the subject matter forming the present invention: F designates a suitable wheeled truck which is provided with a plurality of drums, marked 50 and 60 respectively, which are rotatably mounted side by side on an exposed portion of the truck. Each of these drums is here shown as being mounted on the front of the truck, below the platform or floor of the latter, and is provided with a vertical shaft (51 and 61) having a knurled head (52 and 62) for convenience in turning it. These drums have their peripheral surfaces suitably provided with indices of any suitable nature, such as the numbers illustrated, for example. Other suitable indices correspond-

ing to those on the peripheral surfaces of the drums are arranged around the axial shafts of the drum and contiguous to the upper surface of the latter. Pointers 53 and 63 are arranged to coöperate with the upper indices to indicate when the drums have been turned to expose the proper indices on the circumferential sides of the drums, the pointers and said upper indices being relatively movable. Preferably, the upper series of indices are carried by indicating disks or dials (54-64) which move with the drums, the pointers (53-63) in such case being fixed in position.

15 One of these drums may relate to the train and the other to the car of that train. Thus, the indication shown in Fig. 3 may be assumed to disclose to the attendant that the packages on that track are intended for car 20 No. 3 of train No. 2. The proper attendant observing this indication will set his switch to divert the truck from the main line to the branch line which leads toward the several cars numbered 3, and at a proper time, 25 which may be immediately upon the delivery of the truck by the switch, or later according to circumstances, said truck will be taken to car number 3 of train 2 and emptied. The truck when emptied is then re- 30 turned to the main line, which returns it to a loading station. If the car referred to contains packages to be delivered to another train, in waiting, or to any other unloading station, such packages are placed thereon 35 and the indicator is properly set, before the truck is returned to the main line. Again, an attendant may divert an empty truck from the main line, when he has packages to be delivered to another car or the station 40 or shed, or may divert a truck containing packages when he has others intended for the same destination.

To protect the indicators and at the same time avoid the disadvantages of their occupancy of floor space, each is arranged as stated below the floor of the truck, and their heads (52 and 62) are mounted in sleeves (marked 55 and 65) through which they are accessible from above, the dials being below 50 and projecting beyond the edges of the contiguous transverse member 17 of the truck frame, while the designations of the indicating drums are exposed through openings (marked 56 and 57) in the plate 58.

55 While the present invention has been exemplified in its application as a part of a system in which the truck is propelled by an external chain, it is apparent that it may be embodied as a part of a system in which 60 the truck is driven electrically, by power derived from an external source, and its application as a part of such system is contemplated to be within the spirit of the invention and the scope of the subjoined 65 claims.

Having now described the invention what I believe to be new and desire to secure by Letters Patent, is:

1. A wheeled truck provided with a plurality of independently rotatable drums 70 having indicating elements thereon coöperatively indicating the destination of the truck, the elements on one drum indicating receiving stations and the elements on the other drum indicating units of said stations, 75 and means on the truck through which selected indications of both drums are simultaneously exposed while the other elements on both drums are concealed.

2. A truck provided with a plurality of 80 indicating drums having independently-operable means for adjusting the same, said drums coöperatively designating the destination of the truck, said truck having a floor member which is arranged over said drums and protects the same, the truck also having its front member provided with an opening for each drum, each of said openings being arranged to expose one indicating element of its drum at a time. 85

3. A wheeled truck provided with a plurality of independently rotatable drums having indicating elements thereon coöperatively indicating the destination of the truck, the elements on one drum indicating receiving stations and the elements on the other drum indicating units of said stations, 90 said drums being mounted side by side and each having a shaft provided with a head for convenience in turning it, and means separate from said indicating elements for indicating the positions of the drums, the said means including, for each drum, relatively movable elements, each movable element of the means turning with its corresponding drum. 95

4. A wheeled truck provided with a plurality of independently rotatable drums having indicating elements on the peripheral surfaces thereof coöperatively indicating the destination of the truck, the elements on one drum indicating receiving stations and the elements on the other drum indicating units of said stations, 100 said drums being mounted side by side and each having a shaft provided with a head for convenience in turning it, each drum also having a separate set of indicating elements mounted on a surface thereof which is at an angle to the first set of indicating elements and corresponding to the latter, and means co-operating with the second set of indicating elements for indicating the positions to which the drums have been set. 105

5. A truck having a plurality of indicating drums, said drums being mounted below the floor of the truck, on vertical axes and side by side, and having their axial shafts provided with heads for turning them, the circumferential surface of each drum hav- 110 115 120 125 130

ing a plurality of indicating elements, a second set of indicating elements, the second set of indicating elements corresponding to the first sets and being arranged adjacent to the upper surfaces of the respective drums and around the axial shafts of the latter, and means coöperating with said second sets of indicating elements to indicate the positions to which the drums have been adjusted, the front and floor of the truck respectively having openings through which indicating elements are exposed.

6. A truck, a drum mounted at the front thereof and having its forward surface adjacent to said front provided with a set of indicating elements, the front of the truck having an opening through which the indicating elements are individually exposed, said drum also having its axial shaft provided with a head for convenience in turning it, a sleeve surrounding the headed portion of the shaft, said sleeve being open to give access to the head, a second set of indicating elements and a coöperating element

for indicating the position to which the truck has been adjusted, said second set of indicating elements being arranged around the axial shaft of the drum and adjacent to a surface of the latter, the second set of indicating elements and its said coöperating element being arranged for relative movement, the indicating elements on one of said drums indicating a set of receiving elements and the indicating elements on the remaining drum indicating a unit of such set, and said truck having a member which partially covers the drum and protects the latter, said member having an opening alined with the opening in the sleeve for giving access to the latter.

In testimony whereof I have hereunto set my hand in presence of two subscribing witnesses.

MORRIS U. BERNHEIM.
